UNITED STATES PATENT OFFICE.

CLYDE P. WAGNER AND GEORGE C. WIEMER, OF JOPLIN, MISSOURI.

LIQUID-FUEL BURNER.

1,366,980.

Specification of Letters Patent.

Patented Feb. 1, 1921.

Application filed December 27, 1919. Serial No. 347,722.

To all whom it may concern:

Be it known that we, CLYDE P. WAGNER and GEORGE C. WIEMER, citizens of the United States, residing at Joplin, in the 5 county of Jasper and State of Missouri, have invented certain new and useful Improvements in Liquid-Fuel Burners, of which the following is a specification, reference being had to the accompanying drawings.

This invention relates to certain improvements in liquid fuel burners and has relation more particularly to a device of this 15 general character embodying the use of oil and steam or air and it is an object of the invention to provide a device of this general character with a novel and improved converting chamber wherein the mixture is effectively transformed or converted into a 20 gas.

It is also an object of the invention to provide a novel and improved device of this 25 general character operating in a manner whereby the flame burns without smoking under all conditions and particularly when initially burning in connection with a cold furnace or the like.

It is also an object of the invention to provide a novel and improved burner of this 30 general character including an atomizer and a mixing chamber arranged immediately in advance of the atomizer whereby the efficiency of the device is materially increased.

Another object of the invention is to provide a device of this general character including a novel and improved atomizer comprising a housing having arranged there-in a plurality of blades mounted and arranged in a manner to assure the requisite 40 conversion or transforming of the mixture into gas.

The invention consists in the details of construction and in the combination and arrangement of the several parts of our improved liquid fuel burner whereby certain 45 important advantages are attained and the device rendered simpler, less expensive and otherwise more convenient and advantageous for use, as will be hereinafter more 50 fully set forth.

The novel features of our invention will hereinafter be definitely claimed.

In order that our invention may be the better understood, we will now proceed to 55 describe the same with reference to the accompanying drawings, wherein:

Figure 1 is a fragmentary view partly in section and partly in top plan of a burner constructed in accordance with an embodiment of our invention.

60

Fig. 2 is a view partly in section and partly in elevation illustrating the sleeve and the parts concomitant thereto as herein disclosed.

Fig. 3 is a fragmentary sectional view of 65 the end portion of the housing of the atomizer to which the sleeve is engaged.

Fig. 4 is a view in end elevation of the outer end of the housing of the atomizer.

Fig. 5 is a view in elevation of the inner 70 end of the housing of the atomizer.

Fig. 6 is a view partly in elevation and partly in section with a burner as herein included and particularly illustrating the means for delivering the oxygen containing 75 fluid through the mixing chamber.

Fig. 7 is a view in top plan of a modified form of shaft and blades within the atomizer; and

Fig. 8 is a view in plan of a still further 80 modified form of a shaft and blades for use within the atomizer.

As disclosed in the accompanying drawings, A denotes a four-way union having suitably coupled to the opposed branches 1 85 the oppositely directed pipe lines P embodying the returned portions P' coupled to the opposite branches 2 of a T-union B. Suitably coupled to the intermediate branch 2^a of the union B is the pipe line L leading from a 90 source (not shown) of steam or air or a mixture of both under pressure. Interposed in the line L is a controlling valve V.

Coupled to one of the branches 1^a of the union B is a pipe line O leading from a 95 source of oil supply and the opposed branch 1^a has coupled thereto a pipe length or section S. Engaged with the outer or opposite end portion of the pipe length or section S is a tubular head or casting H, affording a 100 mixing chamber M and with which the pipe S communicates. Interposed in the pipe line O is a controlling valve V' of a conventional type.

The first named branch 1^a of the union A 105 has applied therein a plug 25 and disposed axially through said plug and in communication with the pipe line O is a tubular member or pipe 26 which extends through the opposed branches 1^a through the pipe 100 length or section S and into the mixing chamber M. The tubular member or pipe

26 is of a major diameter materially less than the mean diameter of the branches 1^a and the pipe length or section S.

Suitably secured to the end portion of the tubular member or pipe 26 within the mixing chamber M is a nozzle or head N provided in its side wall with the slots 3 whereby the oil is discharged from said head or nozzle N in directions substantially radial 10 to the longitudinal axis of the tubular member M or pipe 26.

The head or casting H, at a point substantially diametrically opposed to the connection between the said head or casting H and the pipe length of section S, is provided with 15 an opening 4 in which is snugly engaged an end portion of the housing 5 of the atomizer C.

The housing 5 as herein disclosed comprises an elongated tubular member having the end inserted within the opening 4 intersected by a radially directed cross arm 6, preferably integrally formed with the housing 5 and provided at substantially its 25 longitudinal center with an opening 6^a.

The opposite end portion of the housing 5 is provided with the substantially diametrically opposed and longitudinally directed open end grooves or channels 7. The base 30 portion of each of said grooves or channels 7 adjacent to its closed end is provided with a pocket or recess 8. The periphery of said housing 5 at such end portion is also provided with the threads 9 to afford means 35 whereby the large end of the reducing union 10 may be effectively engaged with the housing 5.

The outer or smaller end portion of the union 10 is interiorly threaded as at 11 and 40 with which threads are engaged the inserted end portion of a gas pipe 12 of desired length and which pipe 12 has suitably engaged with its outer end the tip 14 of any ordinary or preferred type.

45 15 denotes a sleeve from which diverge the arms 16, the free end portions of said arms terminating in the substantially parallel portions 16^a adapted to snugly fit within the grooves or channels 7 produced in the housing 5. The portion 16^a of the arms terminate in the inwardly directed lugs 17 which extend within the recesses or pockets 8 hereinbefore referred to. The outer faces 50 of the portions 16^a are provided with the threads 18 which, when the arms 16 are in applied position, are in continuation of the threads 9 so that when the reducing coupling 10 is in applied position, the arms 16 are effectively secured to the housing 5 and the 55 sleeve 15 maintained at substantially the axial center of the housing 5 and at a point 60 slightly in advance thereof.

In threaded engagement within the sleeve 15 through the outer end thereof is a shank

19 which serves as an adjustable bearing 65 for the shaft 20.

A shaft 20 extends longitudinally through the housing 5 and has one end portion extending within the opening 6^a in the cross arm 6 whereby said arm 6 serves as a bearing for the shaft 20. The opposite end portion of the shaft 20 extends into the sleeve 15 through the inner end thereof and is engaged by the inserted end of the shank or bearing 19. The shaft 20 is also provided 70 with an outstanding annular shoulder 21 which bears against the inner face of the cross arm 6 whereby said shaft 20, through the instrumentality of the shank or bearing 19, is effectively maintained in working or 75 applied position.

The shaft 20 inwardly of but in close proximity to the shoulder 21 is provided with the propeller blades 22 so that the pressure of the mixture entering within the 80 housing 5 will cause the shaft 20 to rotate at a relatively high speed. The shaft 20 within the housing 5 is provided with the longitudinally spaced blades 23 arranged in pairs with the blades of each pair substantially 85 diametrically opposed. Adjacent blades 23 are also substantially perpendicularly related. As is particularly illustrated in Fig. 1, the blades 23 are substantially flat with their faces disposed longitudinally of the 90 shaft 20 and each of the blades 23 is provided with a plurality of longitudinally spaced openings 24. As the shaft 20 rotates within the housing 5, the blades 23 operate to effectively convert or transform the mixture into a gas before said mixture enters the pipe 12. This particular type of blades 23 is especially adapted for use when the pressure is from twenty to seventy-five 95 pounds. With a pressure between two and 100 seventy-five pounds, it is preferred that the blades 23^a be imperforate and of substantially spiral formation. With a pressure between seventy-five and two hundred 105 pounds, the spiral blades 23^b are preferably 110 used and which blades are also substantially spiral in form but the coaxing shaft 20' is not provided with the propeller blades.

With a burner constructed in accordance with an embodiment of our invention, it 115 has been fully established in practice that the flame burns without smoke and even when initially burned in connection with a cold furnace or the like. It has also been fully demonstrated in practice that the gas 120 will also readily ignite in a cold furnace or the like. It has also been determined by actual use that our improved burner as herein disclosed results in a material saving in fuel with the respect to the same general character of burners now in use.

From the foregoing description, it is thought to be obvious that a liquid fuel

burner constructed in accordance with our invention is particularly well adapted for use by reason of the convenience and facility with which it may be assembled and operated, and it will also be obvious that our invention is susceptible of some change and modification without departing from the principles and spirit thereof, and for this reason we do not wish to be understood as limiting ourselves to the precise arrangement and formation of the several parts herein shown in carrying out our invention in practice except as hereinafter claimed.

15 I claim:

1. A liquid fuel burner comprising a mixing chamber provided with means for admitting therein at different points oil and a fluid under pressure containing oxygen, an atomizer in communication with the mixing chamber, and a burner in communication with the atomizer, said atomizer including therein a plurality of blades supported for rotation about an axis extending in the same general direction as the flow of the mixture therethrough, said blades extending longitudinally of said axis, said blades being arranged in pairs, the blades of each pair being substantially diametrically opposed.
2. An atomizer for a fuel burner comprising a housing adapted for communication with a mixing chamber and adapted to deliver to a tip, a cross member intersecting one end portion of the housing, a sleeve positioned adjacent the opposite end portion of the housing and provided with arms extending in a direction longitudinally of the sleeve, means for engaging said arms with the adjacent end portion of the housing, a shaft rotatably supported by the cross member and the sleeve, and blades carried by the portion of the shaft within the housing.
3. An atomizer for a fuel burner comprising a housing adapted for communication with a mixing chamber and adapted to deliver to a tip, a cross member intersecting one end portion of the housing, a sleeve positioned adjacent the opposite end portion of the housing and provided with arms ex-

tending in a direction longitudinally of the sleeve, means for engaging said arms with the adjacent end portion of the housing, a shaft rotatably supported by the cross member and the sleeve, and blades carried by the portion of the shaft within the housing, and an adjustable bearing carried by the sleeve and coacting with the shaft.

4. An atomizer for a liquid fuel burner comprising a housing adapted for communication with a mixing chamber and adapted to deliver to a tip, a bearing carried by one end portion of the housing, the opposite end portion of the housing being provided with grooves extending longitudinally thereof, a sleeve positioned adjacent second named end portion of the housing and provided with arms extending outwardly therefrom, the outer end portion of the arms seating within the grooves of the housing, means for holding said arms within the grooves, and a blade carrying shaft extending through the housing and rotatably supported by the bearing and the sleeve.

5. An atomizer for a liquid fuel burner comprising a housing adapted for communication with a mixing chamber and adapted to deliver to a tip, a bearing carried by one end portion of the housing, the opposite end portion of the housing being provided with grooves extending longitudinally thereof, a sleeve positioned adjacent second named end portion of the housing and provided with arms extending outwardly therefrom, the outer end portion of the arms seating within the grooves of the housing, means for holding said arms within the grooves, and a blade carrying shaft extending through the housing and rotatably supported by the bearing and the sleeve, a wall of each of the grooves being provided with a recess, the portion of the arm seating within the groove being provided with a lug extending within the recess.

In testimony whereof we hereunto affix our signatures.

CLYDE P. WAGNER.
GEORGE C. WIEMER.
